UNITED STATES PATENT OFFICE.

GEORGE HERBERT SKINNER, OF EALING, LONDON, ENGLAND.

INTERNAL-COMBUSTION ENGINE.

1,321,132.

Specification of Letters Patent. Patented Nov. 11, 1919.

Application filed February 12, 1919. Serial No. 276,548.

To all whom it may concern:

Be it known that I, GEORGE HERBERT SKINNER, a subject of the King of Great Britain, residing at 15 Woodville road, Ealing, in the county of London, England, have invented certain new and useful Improvements in or Relating to Internal-Combustion Engines, of which the following is a specification.

10 This invention relates to devices which enable a rich explosive mixture independent of or supplementary to that supplied by the ordinary carbureter to be introduced into the engine to facilitate starting of the 15 engine particularly when the latter is cold.

The chief object of the present invention is to provide an improved device of this kind which enables the induction pipe and cylinder to be primed with a suitable liquid 20 fuel prior to the admission of a rich explosive mixture suitable for starting. The improved device is also constructed to enable air only to mix with the mixture supplied by the ordinary carbureter during the 25 normal running of the engine for the purpose of economizing in the consumption of liquid fuel as heretofore proposed in devices of this kind; the independent or supplementary mixture may be supplied at any 30 time during the running of the engine to enrich the ordinary running mixture or the improved device may serve as an emergency carbureter in the case of the ordinary carbureter becoming defective.

35 According to this invention the improved device is provided with a valve which controls a liquid fuel supply and an air supply which device is formed with a receptacle into which a quantity of liquid fuel can be 40 introduced and from which it is drawn into the engine cylinders prior to the admission of the air which in entering the device mixes with liquid fuel from the said fuel supply so as to form the supplementary or starting 45 mixture. The aforesaid receptacle is mounted on a suitable part of the device which part is formed with openings or ports through which the liquid fuel flows into the receptacle and through which the air is 50 drawn after the fuel in the receptacle has been drawn into the cylinder. By means of this invention the induction pipe and cylinder are first charged or primed with liquid fuel drawn from the receptacle prior to 55 the admission of air through the aforesaid

air ports and immediately the liquid fuel has left the receptacle the air flows through the ports and mixes with liquid fuel from the fuel supply so as to form the rich starting mixture which is supplied to the engine cylinder immediately after the latter has been primed as aforesaid so that in this manner the starting of the engine is facilitated and effected almost instantaneously even in the case of an engine which 60 has not been working for a prolonged period. At any time during the running of the engine on the mixture supplied by the ordinary carbureter the said valve may be adjusted to admit the supplementary mixture 70 should any occasion arise when it is desired to enrich the mixture supplied by the ordinary carbureter and in some instances, for example, in the event of the ordinary carbureter or the main fuel supply failing or becoming defective, the engine may be run entirely on the mixture supplied by the improved device, in which case it serves as an emergency carbureter. The controlling valve may if desired be adjusted to enable 75 air only to be supplied to the engine induction pipe or passage through the aforesaid air ports or through an additional air port thus providing an auxiliary air supply for the purpose of economizing in the consumption 80 of fuel.

The device may be constructed as a fitting or attachment which may be readily secured to the engine induction pipe or passage or it may be incorporated in a carbureter to provide the supplementary or independent supply as aforesaid. It may receive the fuel from a main fuel tank or from an independent tank (which may contain petrol when the main tank contains paraffin or other similar fuel) and it may be used with or without a float chamber, or it may receive the fuel from the float chamber of the ordinary carbureter.

In order that the invention may be clearly understood and readily carried into effect I will describe the same more fully with reference to the accompanying drawings in which:

Figures 1 and 2 are vertical sectional views taken at right angles to each other illustrating one form of the invention.

Figs. 3 and 4 are similar to Fig. 2 showing the controlling valve of the device in different positions.

Figs. 5 and 6 are respectively a vertical sectional view and an end view of a modified form of the invention.

Figs. 7, 8 and 9 are fragmentary sectional views illustrating different positions of the controlling valve.

Fig. 10 shows one construction of the device attached to the float chamber of a carburetor.

10 A represents the casing of the device which at its upper parts is formed with a lateral extension having an inlet passage B adapted to be connected in any suitable appropriate manner to a source of fuel supply, the said passage B being in communication with a central passage C in the casing which passage C may be controlled by an adjustable needle valve D. The lower part of the casing A is formed with a passage E which by means of holes F opens into an open shallow receptacle G secured to the lower part of the casing A. The middle part of the casing as shown in Figs. 1 and 2 is shaped to receive a tapered valve 20 or plug H having an axial passage I and two radial passages J, K which latter are adapted to register respectively with the passages C, E in the casing. The casing A is also formed with an extension L adapted to be screwed into the engine induction pipe or the wall of the induction pipe and provided with an outlet passage M co-axial with the axial passage I in the valve or plug H. The said valve 30 H is pressed against its seating in the casing by means of a spring N interposed between it and an end cover or nut O and surrounding an extension or pin P on the valve H which passes through the end cover 35 O and carries an arm Q which is connected by a suitable rod or link to a handle or the like on the dash board of the car. By moving the said handle, the arm Q and the valve H can be angularly displaced to set the valve in any required position. In 40 the case of cars fitted with mechanical or other starting contrivance the aforesaid device may be connected thereto so as to operate when the starting contrivance is actuated.

Supposing it is desired to start the engine, the valve H is adjusted to the position shown in Fig. 2 so that its passages J, K place the passage E of the casing in communication with the inlet passages C and B in the upper part of the casing A. Owing to the passage B being connected to a fuel supply such as an auxiliary tank containing say petrol and disposed at a 50 higher level than the device, petrol will flow from the tank through the passages B and C and through the passages J, K in the valve into the passage E whence it will flow through the holes F into the receptacle G. The ordinary throttle valve having

been closed to cut off the ordinary carburetor and upon the crank shaft being rotated by hand or by a mechanical starter, the suction produced by the moving pistons will suck into the induction pipe or passage 70 the petrol from the receptacle G through the passage E, the passages I and K in the valve and the passage M leading into the induction pipe or passage with result that the latter becomes primed with petrol. 75 The continued suction, will, after emptying the receptacle draw in air through the holes F and the passage E, which air will mix with the supply of petrol flowing from the inlet passages B and C thus forming 80 a rich gaseous mixture suitable for starting which being introduced after the priming of the induction pipe and passages into the engine cylinders enables a very quick starting to be effected even though 85 the engine be cold. After the engine has started and is properly running the throttle valve may be opened and the ordinary carburetor brought into use, at which time the starting device may be cut out by moving 90 the valve H into the position shown in Fig. 4 so as to close the passages J, K in the valve and thus cut off the supplementary fuel and air supply. It may be desired to maintain the supplementary supply 95 until the engine is thoroughly warm and able to run satisfactorily on the mixture supplied by the ordinary carburetor and during the time the engine is running to warm up, the ordinary carburetor may remain cut out by keeping the throttle valve closed or the latter may be opened so that the mixture from the carburetor is also supplied. The supplementary or independent mixture from the device may be 100 supplied at any time during the running of the engine to enrich the mixture supplied by the carburetor or in the event of the latter becoming defective or for any other reason and the engine may be kept 105 running entirely on the supplementary or independent supply.

The casing A may be provided with an additional air port R and at any time when the engine is running properly on the mixture supplied by the ordinary carburetor the valve H may be moved to the position shown in Fig. 3 in which the passage K registers with the port R and the passage J does not register with the fuel inlet passage C in the casing, so that additional air is introduced into the engine cylinders, for the purpose of economizing in fuel. Instead of having an additional air port such as R an additional passage similar to the 120 passage K may be provided in the valve H so that the additional passage in the valve may be brought to register with the passage E (at which time the passage J would be closed) enabling the additional air to be 125 130

drawn in through the holes F and the passage E in the casing A.

The modification shown in Figs. 5 and 6 is generally similar to that above described and similar reference letters are used to denote corresponding parts; in this case however, a cylindrical or disk type of valve is employed instead of a tapered plug. For this purpose a disk S of suitable material such as cork is fixed in the casing to form a stationary seating against which the disk valve H is pressed by a spring N the seating having a hole S' which registers with the fuel inlet passage C, a second hole S² for registering with the outlet passage M and a third hole S³ which registers with a port E' leading from the air passage E in the lower part of the casing. The disk valve H is formed with a radial fuel passage J having a lateral opening J' for registering with the passage C, the passage J leading into an opening K which has an axial port I communicating with the outlet passage M and a slot K' which communicates with the passage E through the port E'. When the disk valve H is in the position shown in Figs. 5 and 7 the fuel flows through the inlet passages B and C in the casing through the valve into the passage E into the receptacle G from which the fuel may be drawn for priming the engine induction pipe, as described in connection with the previous example, after which the starting mixture of fuel and air is supplied to the engine induction pipe. When the valve is moved into the position shown in Fig. 9, its passage J and slot K' are closed, this position corresponding to the position of the valve shown in Fig. 4 in connection with the previous modification. When it is desired to admit an additional supply of air the disk valve H is moved to the position shown in Fig. 8 in which the port J' and passage J are closed and the slot K' is still in communication with the port E' so that the additional air is drawn through the holes F and the pipe E, through the valve into the passage and the induction pipe.

The invention is particularly useful when paraffin or other heavy fuel is employed as the main fuel in which case the inlet passage B is connected to a small tank containing petrol so that a suitable mixture of petrol and air can be introduced into the cylinder for starting the engine, which after starting and when it is running properly can be supplied with the paraffin mixture. The device is equally suitable when the main fuel is petrol and in such case the inlet passage may be connected to the main tank or to an auxiliary tank and in all cases the device may be used with or without a float chamber.

The use of the device for starting and

preliminary running as aforesaid enables a considerable saving of fuel to be effected by so adjusting the ordinary carburetor that the mixture is correct when the engine, carburetor, etc., is thoroughly warm and is running most economically. Usually the ordinary carburetor has to be set so that the mixture is rich enough to start when cold or if a start is obtained by other means such as by pouring in petrol, the engine has to be run for quite a considerable time while the car is stationary in order to warm up the engine sufficiently to give the required power.

Instead of constructing the device as a separate unit as above described it may be built to form an integral part of a carburetor or it may be attached to the float chamber of the carburetor. An example of the device attached to the float chamber of a carburetor is shown in Fig. 10. As shown the receptacle G is attached to the float chamber G' of the carburetor and a pipe G² leads from the said chamber to the passage E which has ports F in its lower part as in the previous modifications. Thus, when starting the engine the liquid fuel flows from the float chamber G' into the receptacle G until the levels in the chamber and receptacle are the same. Then by rotating the engine shaft and producing the suction effect the liquid fuel in the receptacle is drawn through the passage E and a passage H' in the valve H through a pipe L to the engine side of the throttle valve which at this time may be closed as previously explained. Thus the induction pipe and engine cylinder can be primed with liquid fuel and after the receptacle has been emptied air is sucked through the ports F and mixes with the fuel sucked through the pipe G² to form the supplementary mixture. The pipe G² as shown, can be controlled by a needle valve D. When desired the valve H can be adjusted by the lever Q to shut off the supply of fuel and air and it can also be adjusted to admit air only by moving it to a position in which its passage H' registers with the air port R so that air is drawn into the pipe L through the branch passage in the valve H.

What I claim and desire to secure by Letters Patent of the United States is:—

1. Apparatus for starting and supplying supplemental fuel mixture to an internal combustion engine comprising a receptacle adapted to receive a priming charge of liquid fuel, a fuel inlet for supplying liquid fuel to said receptacle, a valve in said fuel inlet, an outlet for conducting said fuel from the receptacle to the engine cylinder, said outlet and said inlet having a portion of each in a common passage, a control valve for said outlet, and an air inlet adapted to be sealed by the fuel in said receptacle,

- 4
- said air inlet adapted to admit air to the engine cylinder through the outlet valve when the priming charge is withdrawn from the receptacle, said air inlet also adapted to furnish air to mix with fuel, in said common passage, from the fuel inlet to form a fuel mixture which is conducted to the engine cylinder through said outlet controlled by the outlet valve.
- 10 2. Apparatus for starting and supplying supplemental fuel mixture or air, to an internal combustion engine comprising a receptacle adapted to receive a priming charge of liquid fuel, a fuel inlet passage for supplying a liquid fuel to said receptacle, a control needle-valve for said fuel in said passage, an outlet passage for conducting the fuel from the receptacle to the engine cylinder, said outlet passage and inlet passage having a portion of each in a common passage, an air inlet adapted to be sealed by the fuel in said receptacle, said air inlet adapted to admit air to the engine cylinder when the priming charge is withdrawn from the receptacle, said air inlet also adapted to furnish air to mix with fuel, in said common passage, from the fuel inlet, to form a fuel mixture which is conducted to the engine cylinder through said outlet, a control valve adapted to close said outlet to the receptacle, and an auxiliary air port controlled by said outlet valve adapted to furnish air only to the engine cylinder through the outlet passage when the outlet control valve is positioned to close the outlet to the receptacle and is positioned to open the auxiliary port to the outlet.
- 15 3. Apparatus for starting and supplying supplemental fuel mixture to an internal combustion engine comprising a carburetor, a receptacle adapted to receive a priming charge connected by means of an inlet passage to the carburetor, so as to receive liquid fuel therefrom, a valve in said fuel inlet, an outlet passage for conducting said fuel from the receptacle to the engine cylinder, said outlet passage and inlet passage having a portion of each in a common passage, an air inlet adapted to be sealed by the fuel in said receptacle, said air inlet adapted to admit air to the engine cylinder when the priming charge is withdrawn from the receptacle, said air inlet also adapted to furnish air to mix with fuel from the fuel inlet to form a fuel mixture which is conducted to the engine cylinder through said outlet, and a control valve for said outlet adapted to close the outlet to the receptacle.
- 20 In testimony whereof I affix my signature.
